UNITED STATES PATENT OFFICE

133,433

DESIGN FOR A COMBINED CARD AND RIBBON DISPLAY UNIT OR THE LIKE

John R. Fridlington, Teaneck, N. J., assignor to W. & G. Ribbon Co., Inc., New York, N. Y., a corporation of New York

Application May 23, 1942, Serial No. 106,983

Term of patent 14 years

To all whom it may concern:

Be it known that I, John R. Fridlington, a citizen of the United States and a resident of Teaneck, in the county of Bergen and State of New Jersey, have invented a new, original, and ornamental Design for a Combined Card and Ribbon Display Unit or the like, of which the following is a specification, reference being had to the accompanying drawing, forming part thereof.

In the drawing:

The figure is a front perspective view of the combined card and ribbon display unit or the like, showing my new design.

I claim:

The ornamental design for a combined card and ribbon display unit or the like, as shown.

JOHN R. FRIDLINGTON.
